UNITED STATES PATENT OFFICE.

JOHN P. NEFF, OF EAST ORANGE, NEW JERSEY, ASSIGNOR TO AMERICAN ARCH COMPANY, A CORPORATION OF DELAWARE.

FIRE-BOX ARCH AND ARCH BRICKS THEREFOR.

Application filed February 6, 1920. Serial No. 356,653.

To all whom it may concern:

Be it known that I, JOHN P. NEFF, a citizen of the United States, residing at East Orange, in the county of Essex and State of New Jersey, have invented certain new and useful Improvements in Fire-Box Arches and Arch Bricks Therefor, of which the following is a specification.

This invention relates to refractory arches and arch bricks for fire boxes, and particularly to that style of arch wherein the bricks are rested upon supporting bars or tubes such, for example, as the circulation tubes frequently utilized in locomotive fire boxes. The construction of my invention is particularly useful in connection with fire boxes wherein the supporting or circulation tubes are set at an unusually steep angle.

It is the primary object of my invention to provide an arch, the bricks of which are so constructed and positioned as to cause them to tightly grip the supporting tubes in order to prevent any possibility of displacement under the influence of the draft or on account of the steepness of the angle at which they rest. Furthermore, I have so constructed the bricks that the greater the displacing force the greater will be the gripping action and the more tightly and securely will the arch be held in position.

Another object of the invention is the provision of an arch composed of a plurality of bricks arranged in pairs, each pair being supported between two tubes and each brick being constructed with a tube engaging surface on one edge and an oblique brick engaging surface on the other edge, the bricks being reversible so as to bring the brick engaging surfaces together in each pair of bricks. A still further object of the invention is the provision of bricks which, when placed together in pairs as specified, will be adjustable to variations in tube spacings.

Still another object of the invention is the provision of a brick constructed with a support engaging surface on one edge and a brick engaging surface on the other edge obliquely disposed with respect to the edge having the support engaging surface, and with its ends diverging from the edge having the support engaging surface to the edge having the brick engaging surface, the bricks so constructed being adapted to be reversely arranged in pairs, each pair being

supported between two tubes. The pairs are preferably arranged in rows transversely of the fire box and where bricks with diverging ends are used this arrangement produces a series of perforations through the arch, which perforations surround the tubes. 60

These, together with such other objects as are incident to my invention or may hereinafter appear, I obtain by means of a construction, illustrated in preferred form in the accompanying drawing, wherein—

Figure 1 is a vertical longitudinal section through a fire box illustrating my invention as supported upon circulation tubes; Figure 2 is a horizontal section through a portion of the fire box taken on the line 2—2 of Figure 1; Figure 3 is an enlarged plan view of a pair of bricks embodying my invention and Figure 4 is an end elevation of Figure 3. Figure 5 is a view similar to Figure 1 but showing bricks constructed to make an imperforate arch, and Figure 6 is a section taken on the line 6—6 of Figure 5; and Figures 7 and 8 are details of the bricks used in the structure shown in Figures 5 80 and 6.

The drawings illustrate my invention as applied to a locomotive fire box which comprises the usual crown sheet 1, inside and outside back sheets, 2 and 3, side sheets 4, flue sheet 5, forward water leg 6, and rear water leg 7 between the back sheets 2 and 3. A series of brick supporting and circulation tubes 8 connect the forward water leg 6 to the rear water leg 7, the connection with the rear water leg being at a point above the fire door opening 9. These circulation tubes, it will be noticed, are so bent and set that the angle of inclination from front to back is quite sharp, the angle at the forward portion being especially steep. Attention is called to this fact inasmuch as my invention is particularly useful where this condition exists. 95

The arch A is composed of a plurality of body bricks 10 and a series of wing bricks 11 at each side of the fire box. Each of the body bricks is provided on one edge with a support or tube engaging surface 12 which I prefer to form in the shape of a socket, 100 as shown, which engages substantially one half the circumference of the tube. The other or opposite edge is provided with a brick engaging surface 13, obliquely disposed with respect to the edge having the 110

- support engaging surface. As shown in Figs. 1 to 4 the ends of the brick 14 and 15, and its upper and lower faces, 16 and 17, diverge from the edge having the support engaging surface to the edge having the brick engaging surface. This construction, of course, makes the edge having the brick engaging surface considerably longer than the other edge and the brick considerably thicker on one side than on the other side. The end 15 of the brick is more or less irregularly formed, as shown, its principal irregularity being the result of the cut away portion 18. In Figs. 5 to 8, inclusive, the body bricks 10' are not formed with the cut away portion 18 nor with an irregular end as in Figs. 1 to 4 inclusive, and, therefore, the arch which they create is imperforate. In other respects, however, they embody the essential features of the invention.
- The body bricks are preferably counterparts and are arranged in pairs between tubes. Transversely of the fire box the pairs are arranged in rows, the forward row abutting against the boiler wall and the other rows being successively built up against this row toward the rear of the fire box and extending back as far as may be desired. The bricks in each pair, as shown, are reversely arranged so as to bring the brick engaging surfaces in juxtaposition. From this arrangement it will be apparent that any forward movement of the bricks will tend to wedge them more tightly in place. Furthermore, from the formation of the bricks and of their support engaging surfaces, it will be seen that the bricks of a pair arch themselves, so to speak, both upwardly and downwardly so as to prevent displacement by the force of gravity or by the force of the draft through the flues 19. This upward displacement due to the action of the draft must be guarded against with more than usual positiveness in constructions where the arch rests upon tubes which are set at a steep angle as in the present case. It will be noted by the construction shown (see Fig. 4) that the pairs of bricks arch themselves in either direction.
- The oblique brick engaging surfaces in addition to the wedging action which they give, as above pointed out, permit of a certain amount of adjustability so that bricks of one size may be adapted to variations in tube spacings.
- It will be apparent that instead of being counterparts, the bricks of each pair might be of different sizes but complementary, the only qualification being that they maintain substantially the general characteristics outlined above.
- It will be seen that in an arch constructed in accordance with this invention, as shown in Figs. 1 to 4 there will be formed between each pair of bricks, a passageway or perforation 20 next to the tubes. These perforations transversely of the arch are shown in alignment so that there will be an opening or free space completely surrounding the tubes through which the gases of combustion can readily pass. These perforations are the result partly of the divergent ends and partly of the cut away portions 18. The perforations tend to promote better combustion due to the more thorough admixture of the gases.

It will be seen that by this invention I can construct an arch, the bricks of which are easily put in place, and when placed will securely maintain themselves in position and this without the utilization of any interlocking devices such as have been common in practice heretofore.

I claim:

1. A tube supported arch composed of a plurality of counterpart, reversible bricks each of which is provided on one edge with a socket of sufficient depth to embrace the greater part of one half the circumferences of a tube, the opposite edge being cut obliquely with respect to the socketed edge, as and for the purposes set forth.

2. A tube supported arch composed of a plurality of bricks arranged in pairs, each pair being supported between two tubes, and each brick constructed with one edge provided with a socket adapted to embrace a portion of the circumference of a tube, the opposite edge being cut obliquely with respect to the socketed edge, the bricks of each pair being reversely arranged so as to place the two oblique edges together, as and for the purposes set forth.

3. A tube supported arch composed of a plurality of bricks each of which is provided on one edge with a tube supporting surface, the opposite edge being cut obliquely with respect to the supporting surface, as and for the purposes set forth.

4. A brick for a fire box arch construction having one edge of greater dimension than the other, the narrower edge being provided with a supporting surface and the other edge being cut obliquely with respect to the supporting surface, as and for the purposes set forth.

5. A tube supported arch composed of a plurality of bricks arranged in pairs, each pair being supported between two tubes, and each brick having one edge provided with a tube engaging surface and the other edge cut obliquely to the first edge, the oblique edges in each pair of bricks meeting between the tubes, as and for the purposes set forth.

6. A fire box arch composed of a plurality of bricks arranged in pairs, spaced supports for the pairs, each brick provided with a support engaging surface on one edge and a brick engaging surface on the opposite edge,

the brick engaging surface being cut obliquely with respect to the support engaging surface, and the bricks of each pair being adapted to be reversely arranged so as to bring the brick engaging surfaces together.

7. A fire box arch composed of a plurality of bricks, spaced supports for the bricks, each brick being constructed with a support engaging surface on one edge, a brick engaging surface on the other edge, and with its ends diverging from the support engaging surface to the brick engaging surface, the bricks being arranged in pairs in reversed relation, each pair spanning the distance between two supports and there being perforations through the arch between pairs by virtue of the diverging ends.

8. An arch brick constructed with a support engaging surface on one edge, a brick

engaging surface on the other edge obliquely disposed with respect to the support engaging surface, and with its ends diverging from the edge having the supporting surface to the edge having the brick engaging surface.

9. An arch brick constructed with a support engaging surface on one edge, and a brick engaging surface on the other edge obliquely disposed with respect to the support engaging surface, whereby to compensate for variations in the distance between two supports when a pair of such bricks are arranged in reversed relation to span such distance.

In testimony whereof, I have hereunto signed my name.

JOHN P. NEFF.
